COMBINED SPATULA SCRAPER AND CATCH BOWL OR SIMILAR ARTICLE

John M. Keeler, San Fernando, Calif., assignor to S. Jerome Tamkin, doing business under the fictitious firm name of Phillips Manufacturing Co., Los Angeles, Calif.

Filed Apr. 4, 1960, Ser. No. 60,032

Term of patent 7 years

(Cl. D44—29)

Fig. 1 is a perspective view of a combined spatula scraper and catch bowl showing my new design;

Fig. 2 is a top plan view;

Fig. 3 is a front elevational view;

Fig. 4 is a side elevational view; and

Fig. 5 is a bottom view thereof.

I claim:

The ornamental design for a combined spatula scraper and catch bowl or similar article, substantially as shown.
